UNITED STATES PATENT OFFICE.

KARL FRITZ SJÖMAN, OF STOCKHOLM, SWEDEN.

REVERSING MEANS FOR TWO OR MULTI-CYLINDER INTERNAL-COMBUSTION ENGINES.

1,293,564.

Specification of Letters Patent.

Patented Feb. 4, 1919.

Application filed July 10, 1918. Serial No. 244,249.

To all whom it may concern:

Be it known that I, KARL FRITZ SJÖMAN, a subject of the King of Sweden, and residing at 23 Inedalsgatan, Stockholm, Sweden, 5 have invented certain new and useful Improvements in Reversing Means for Two or Multi - Cylinder Internal - Combustion Engines, of which the following is a specification.

10 In two- or multi-cylinder internal combustion engines there are possibilities of reversing the engine with all the cylinders, the said possibilities, however, having not yet been taken care of, but such engines have, 15 hitherto, generally been reversed with one cylinder only. In this case and particularly in ignition chamber engines, generally an additional fuel pump has been employed, which is active at the reversal only.

20 The present invention has for its object to remove the said drawbacks, whereby thus is obtained that engines of the kind in question may be reversed with all the cylinders and that additional fuel pumps or similar damageable devices may be dispensed with.

The invention is characterized, chiefly, by this that a member is interposed in the fuel supply pipes between the pumps and the cylinders, said member taking up, when 30 running the engine in the forward direction, such a position that the fuel will be pumped into the cylinders corresponding to the fuel pumps, but which, in reversing the movement, will be manually or automatically adjusted so that the fuel will be pumped into other cylinders, in which this is advantageous with respect to the position of the pistons at the reversal.

In order to carry out the present invention, obviously many forms of embodiment 40 are possible. One of those is schematically shown in Figure 1 of the annexed drawings showing on a larger scale a longitudinal section through the member. Fig. 2 schematically shows the connection between the member and the cylinders and Fig. 3 shows the 45 same in side elevation. Figs. 4, 4^a and 5 show details.

1 designates a body interposed between 50 the fuel pumps and the cylinders. Movable in a central aperture in the said body is a plunger or similar member 2. The branch pipes 3 and 4 are connected with the fuel pumps, while the branch pipes 5 and 6 are connected with the cylinders. A and B designate the fuel pumps (not shown in Fig. 1)

which are connected with the branch pipes 3 and 4, respectively, and which normally feed the fuel into the cylinders, which, while being not shown in Fig. 1, are designated with 60 C and D, respectively. From the branch pipe 3 a conduit 7 passes to a conduit 9 arranged in the member 2, said conduit 9 being in turn connected with a conduit 8 passing to the branch pipe 5. In a similar manner, 65 the branch pipe 4 is, through conduits 10, 12 and 11, connected with the branch pipe 6. In the movable member 2 there are, besides, two obliquely arranged transverse conduits 13 and 14, so disposed that, when moving 70 the said member, for instance downward in Fig. 1, a certain distance, the conduit 13 connects the conduits 10 and 8, and the conduit 14 connects the conduits 7 and 11.

The drawing shows the position of the 75 said member in running forward. The fuel pump A feeds the fuel into the cylinder C through the conduits 7, 9, 8, and the fuel pump B feeds the fuel into the cylinder D through the conduits 10, 12, 11. When reversing the movement, the member 2 is moved downward (according to Fig. 1) a distance corresponding to the distance between the conduits 7 and 8, whereby the conduit 13 connects the conduits 10 and 8 and 80 the conduit 14 connects the conduits 7 and 11. The conduits 9 and 12 will thus be placed below the conduits 7 and 10, which are thereby shut off from the conduits 8 and 11. When the member 2 is caused, at the 85 reversal, to take up the last-mentioned position, the pump A will thus feed the fuel into the cylinder D through the conduits 7, 14, 11, and the pump B will feed the fuel into the cylinder C through the conduits 10, 13, 8. 95

It is obvious that the same result may be effected by one or, if desired, valves of another construction than that shown in Fig. 1. Thus, for instance, a multi-branch valve, a slide valve or the like may as well be used. 100 The valve may be adjusted manually at the reversal; it is, however, more suitable to connect the same with the hand lever, a cam disk, a friction disk or the like, so that the adjustment of the said valve will be effected 105 automatically at the reversal of the movement.

Figs. 2 and 3 show by way of example, 110 how the valve may be acted upon automatically at the reversal. Fig. 2 shows the motor cylinders and the valve in cross-section and on different scales, the appertaining

parts being shown in elevation. Fig. 3 shows, on an enlarged scale, parts of Fig. 1, viewed from the right.

The motor cylinders are designated with 5 C and D and the motor shaft with 16. To the cylinder D are, according to the drawing (Fig. 2), rigidly secured two fuel pumps A and B, which are connected with the branch pipes 3 and 4 of the valve through pipes 17 and 18, respectively. To the motor shaft 16 are rigidly secured two eccentric disks 19, 20, the movements of which are, by means of rods 21, 22 and angle levers 23, 24, transmitted to two sliding pieces 25, 26, respectively. The sliding pieces are movable on a guide 28 provided with a cam or projection 27, said pieces being held pressed onto the said guide by the elastic and pivotal continuation 2^x of the member 2, which is, by 10 the action of a spring 29 and a lever 30 swingable about a stationary shaft 37, normally held pressed against the sliding pieces, so that the said pieces will, when moving, follow the guide 28. With the one end of 15 the lever 30 is pivotally connected a rod 31 coöperating with a friction disk 34 secured to the shaft 16, the forked shanks 35 of the rod 31 being arranged around the said disk 34. (See Figs. 4 and 4^a, the latter being a 20 view of Fig. 4 from below). The shanks 35, 35 of the rod 31 are normally out of contact with the friction disk 34. The contact between the disk and one of the said shanks is effected first by moving the hand 25 lever 36 in the one or the other direction. When the continuation 2^x of the member 2 bears against the sliding pieces and the latter move along the guide, projections 32 of the sliding pieces co-act with projections 33 30 of the piston rods of the fuel pumps, so that these are pressed inwardly, while, when the member 2 is raised and the pressure of the continuation 2^x on the sliding pieces ceases, the cam 27 imparts to the sliding pieces an 35 upward movement in an oblique direction, so that the latter pass by the projections 33 without acting upon them. The continuation 2^x is pivotally secured to the member 2, so that it is capable of following the movements of the sliding pieces.

Suppose the motor to be set for running forward with an angle of advance of 10 degrees, *i. e.* the fuel to be pumped into the cylinder, when the piston is still to be moved 40 a small part of the stroke, before it reaches the top point. Suppose, further, the friction disk 34 to be rotated in the direction of the arrow in Fig. 4. When the reversal is to be performed, the rod 36 is moved in 45 the direction of the arrow, so that the left shank 35 is brought into contact with the disk and, on account of the friction, will be raised. Hereby, also the rod 31 is raised, and the lever 30 is swung upward against 50 the action of the spring 29, whereby also the

member 2 and the continuation 2^x are raised, so that the pressure on the sliding pieces ceases, and the projections 32 cease to act upon the projections 33. Hereby, the feeding of the fuel decreases, and the speed of 50 the motor will be moderated to a certain degree, at which any of the fuel pumps feeds the fuel through any of the conduits 13 or 14 to that cylinder, the crank of which is diametrically opposite that crank, the cylinder of which, in normal running, ought to have obtained the fuel. The crank of the cylinder obtaining the fuel is at that moment 10 degrees in advance of the lowest point of the stroke. When the piston then 55 approaches the uppermost point of the stroke, an explosion (advanced ignition) is effected, so that the piston is moved backward, before the crank has reached the uppermost point, thus effecting the reversal of 60 the movement. In reversing the movement also the disk 34 changes its direction of rotation, by which the friction between the disk and the shank 35 is checked, so that the rod 31 is lowered and, at the same moment, 65 the member 2 will be moved back to the position of normal running shown in Fig. 2, the fuel being thereby fed in the same manner as before the reversal.

The device for acting upon the reversing 65 means shown in Figs. 2 to 4, is as mentioned, cited as an example only, and the invention is not limited to the said device.

Particularly in ignition chamber engines, the present invention offers considerable advantages. Except the advantages referred to above, is, namely, gained that the said engines may be run light without the use of a heating lamp, since by means of the device described the fuel is supplied half a 70 rotation earlier than has hitherto been the case and, thus, the ignition chamber will be capable of keeping itself sufficiently hot.

Having now particularly described and ascertained the nature of my invention what I 75 claim as new and desire to secure by Letters Patent is:

1. The combination with a plurality of engine cylinders and a fuel pump for each cylinder, of a valve comprising a casing having a central valve passage, an outlet port located on one side of the casing and communicating with one of the cylinders, an inlet port located on the same side of the casing and communicating with one of the fuel pumps, 80 an outlet port located on the other side of the casing and communicating with the other cylinder, an inlet port located on the same side of the casing and communicating with the other pump, passages placing said ports in communication with the valve passage, and an axially slid able valve located in the valve passage and having a groove for placing the inlet port on one side of the casing 85 in direct communication with the outlet port 90

on the same side of the casing when the valve is in one position, said valve having a port for placing the inlet port on one side of the casing in communication with the outlet port on the other side of the casing when the valve is in a different position.

2. The combination with an internal combustion engine and a plurality of fuel pumps having operating stems, of a guide plate having an inclined portion, a plurality of slides movable over said guide plate and adapted to normally engage the pump stems for operating the same, a valve for controlling the fuel supplied by the pumps to the

engine, resilient members carried by said valve and normally bearing upon said slides to maintain them in engagement with the plate, means operated by the engine shaft for actuating said slides, and means for moving the valve and resilient members to permit the slides to reciprocate without engaging the pump stems.

In testimony whereof I have affixed my signature in presence of two witnesses.

KARL FRITZ SJÖMAN.
